[57] **CLAIM**

The ornamental design of a submerged dragon climber, as shown.

DESCRIPTION

FIG. 1 is a perspective view of a submerged dragon climber in accord with my new design, illustrating the complete appearance of the climber which consists of the three illustrated elements,

FIG. 2 is a side elevational view of my new climber as taken from the left of FIG. 1, the opposite side being the mirror image thereof,

FIG. 3 is a top plan view of my new design,

FIG. 4 is a rear elevational view of the new design,

FIG. 5 is a front elevational view of the design; and,

FIG. 6 is a front elevational view of the central element of the design, the opposite side elevational view being the mirror image thereof.
